QUATERNARY AMMONIUM SALTS

Harry James Barber, Dagenham, England, assignor to May & Baker Limited, Dagenham, England, a British company

No Drawing. Application October 18, 1951, Serial No. 252,003. In Great Britain October 27, 1950

3 Claims. (Cl. 260—501)

1

This invention relates to the production of quaternary ammonium compounds.

It is known that therapeutic properties are possessed by many of the bis-quaternary ammonium salts which conform to the general formula:

where R represents a methyl or ethyl group and X represents the residue of an acid. These salts are readily soluble in water and their manufacture in the pure state with good yield is complicated by the difficulty experienced in the removal of soluble by-products.

It is the object of the present invention to provide new intermediates from which the above bis-quaternary ammonium salts can readily be prepared in a good yield on a commercial scale. These new intermediates are salts of the foregoing type in which the groups X are replaced by the radical of 2:2-dihydroxy-1:1-dinaphthyl-methane-3:3-dicarboxylic acid (hereinafter in this specification and in the appended claims this acid is, for convenience, called "embonic acid" while its salts are hereinafter called "embonates"). While embonic acid does not form readily separable salts with quaternary ammonium derivatives such as tetraethyl ammonium or polymethylene bis-quaternary ammoniums containing less than six methylene groups it has been found that the embonates referred to above may be very simply prepared in a pure state.

According to the present invention, these new embonates are obtained through the double-decomposition in aqueous solution of a corresponding bis-quaternary ammonium salt of the aforesaid type by adding to that solution a water-soluble embonate.

The new embonates are very sparingly soluble in water at normal temperatures although they will form solutions of reasonable concentration at elevated temperature. It is, therefore, a simple matter to isolate the new embonates from aqueous solutions in which they are prepared. Since embonic acid itself is substantially insoluble in water even at boiling point the new embonates provide a convenient and simple route to the more soluble corresponding bis-quaternary salts uncontaminated by soluble by-products. Thus embonic acid is precipitated by acidification of a quaternary ammonium embonate leaving the quaternary ammonium salt of the acidifying agent in solution in a substantially pure state.

2

It will be appreciated that the process of the present invention can be regarded as a step in the production of bis-quaternary ammonium salts of the aforesaid general formula in which X represents an anion of an acid other than embonic acid and which are more soluble in water than the corresponding embonate. Thus, in general, the new embonates will be directly isolated from aqueous solution containing one of such salts (for example, sulphate, nitrate, halide or sulphonate) by the addition thereto of a water-soluble embonate such as sodium embonate. In the case, especially, of the quaternary ammonium salts of the aforesaid general formula in which R represents methyl this fact is of considerable commercial importance as will now be explained. Of the theoretically suitable hexamethylene intermediates for the production of these particular quaternary ammonium salts, hexamethylene diamine is to be preferred from the viewpoint of accessibility. Theoretically, this compound could be directly methylated and quaternated in a single operation using, for example, dimethyl sulphate or other reactive methyl ester such as a halide but in actual practice this was hitherto found to possess serious disadvantages arising from the formation of by-products of the methylation reaction (viz. free acids derived from the methylating agents or corresponding salts if acid binding agents have also been used) the separation of which from the desired quaternary ammonium salts is extremely difficult. If, however, a water-soluble embonate is added to the crude reaction mixture in which any free acid has previously been neutralised and from which suspended or precipitated solids (if any) have been removed, the embonate corresponding to the desired salt is precipitated and thereby isolated. After recrystallisation (which may conveniently be effected from water) the embonate can then be converted into the desired salt by treatment with an acid containing the required anion.

The process of this invention is not only applicable to the production of known quaternary ammonium salts of the aforesaid general type as a means for eliminating otherwise necessary purification steps but also renders possible the commercial production of hitherto unknown quaternary ammonium salts of the aforesaid general type that would be difficult to produce by the application of known methods. For example the quaternary ammonium salts containing a radical derived from an acid the anion of which is neither physiologically nor pharmacologically un-

desirable, for example the bitartrates, bisulphates and dihydrogen phosphates are now rendered readily available. Other examples of new salts which can be conveniently prepared using the process of the present invention are adipates (neutral and acid), benzoates, carbonates, chlorides, citrates, acid maleates, methosulphates, succinates (neutral and acid), neutral sulphates and neutral tartrates.

The process of the present invention is illustrated by the following examples:

Example I

Hexamethylene diamine (116 gms.), sodium carbonate (466 gms.), and water (800 mls.) were heated to 60° C., and dimethyl sulphate (830 gms.) added with stirring over 1½ hours keeping the temperature below 90° C. The reaction mixture was then stirred at 90° C. for 2 hours, then cooled to 20° C., acetone (1200 mls.) added and the whole cooled to 0° C.

The solid formed was removed by filtration and washed with acetone (150 mls.). Filtrate and washings were diluted with water to 4 litres and heated to 60° C. under reflux. To this was added a solution prepared from embonic acid (388 gms.), sodium hydroxide (80 gms.) and water (5 litres), the whole refluxed for 10 minutes and thereafter allowed to cool overnight.

The resultant embonate (530 gms.) was filtered off, washed twice with a solution of acetone (75 mls.) in water (425 mls.), and dried at 100° C. to give an amorphous yellow powder, M. P. 290-1° C. (with decomp.). 588 gms. of the embonate was dissolved in boiling water (4 litres). A solution of tartaric acid (300 gms.) in water (1 litre) was added slowly at the boil and the precipitated embonic acid removed by filtering hot and washing twice with hot water (1 litre). The filtrate and washings were evaporated in a steam pan to a thick syrup which was granulated by stirring with ethyl alcohol (1500 mls.). The ethyl alcohol was removed by filtration and hexamethylene 1:6-bis-trimethyl-ammonium bitartrate (400 gms.) was obtained as the monohydrate by recrystallisation from methyl alcohol (700 mls.).

The embonic acid which is regenerated can, of course, be used for the next operation. Owing

to its extreme insolubility, the loss is extremely small.

Example II

The embonate (588 gms.) prepared by the process of Example I was dissolved in boiling water (4 litres). Hydrobromic acid 50% w/w. (325 gms.) diluted with water (2 litres) was added slowly at the boil and the precipitated embonic acid removed by filtering hot and washing twice with hot water (1 litre). The filtrate and washings were evaporated to dryness in a steam pan and the residue recrystallised from ethyl alcohol (1200 mls.), to yield the dibromide (320 gms.) corresponding to the tartrate of Example I.

From an aqueous solution obtained by the quaternation with the appropriate alkyl halide of 1:6-bis-dimethylaminohexane there was obtained in analogous manner to the embonate of Example I hexamethylene-1:6-bis-dimethylethylammonium embonate which crystallised from water as a hydrate and on drying gave an amorphous yellow powder M. P. 262-265° C. (with decomp.).

I claim:

1. A compound of the general formula:

where R represents a member of the class consisting of methyl and ethyl and A represents the residue of 2:2-dihydroxy-1:1-dinaphthylmethane-3:3-dicarboxylic acid (embonic acid).

2. Hexamethylene-1:6-bis-trimethylammonium embonate.

3. Hexamethylene-1:6-bis-dimethylethylammonium embonate.

HARRY JAMES BARBER.
